UNITED STATES PATENT OFFICE

RAYMOND A. TAYLOR, OF FREDERICK, MARYLAND

RETARDING DEVICE FOR PERSONS ESCAPING FROM A SUBMERGED VESSEL

Application filed February 8, 1929. Serial No. 338,484.

The present invention relates to a device for use by persons escaping from a submarine or other submerged vessel having for its prime object to provide means so that the person may regulate the speed at which he rises through the water.

It is well known that if a person with life preserver means and other paraphernalia leaves a submerged vessel at a rather great depth he would rise through the water at a speed entirely too great for safety but with the present apparatus it is possible for such person to regulate the speed at which he rises in the water.

15 A still further very important object of the invention resides in the provision of a device of this nature which is comparatively simple in its construction, strong and durable, inexpensive to manufacture, easy to manipulate, and thoroughly efficient and reliable in use and operation.

With the above and numerous other objects in view as will appear as the description proceeds, the invention resides in certain novel 25 features of construction and in the combination and arrangement of parts as will be hereinafter more fully described and claimed.

In the drawing:

Figure 1 is a vertical section through the 30 apparatus embodying the features of my invention,

Figure 2 is a similar view showing the apparatus collapsed,

Figure 3 is a top plan view thereof,

35 Figure 4 is a perspective view of the post,

Figure 5 is a sectional view through the post substantially on the line 5—5 of Figure 4, and

40 Figure 6 is a perspective view of one of the valves.

Referring to the drawing in detail it will be seen that the numeral 5 denotes a concavo-convex body with the concave side disposed upwardly. This body is collapsible and may 45 be made of any suitable material, the material not being of the essence of the invention.

This body is disposed about a disk 6 from which rises a post 7. A pair of loops 8 are mounted on the upper surface of the disk 6 50 one to each side of the post 7 for receiving the

feet of a person standing on the disk. A plurality of cables 9 are fastened to the outer edge of the body and to a ring 10 fastened to the post 7.

This body 5 is provided with a plurality of 55 openings 11 associated with which are flat valves 12 hingedly mounted at their inner ends on the disk 6. The outer ends of the flat valves that is the free ends thereof have attached thereto cables 14, the upper ends 60 of which are attached to a ring 15 slideable on the post 7 above the ring 10 and having a circular handle bar 16 fastened thereto in any suitable manner so that the person standing on the disk 6 may control the ring 15 65 by the handle bar.

Thus by lifting the handle bar the flat valves are opened. It is preferable to provide cables 17 attached to the free ends of the flat valves 12 and to the body to limit the 70 opening of the flat valves.

In Figure 2 I have indicated in dotted lines an escapement tube 19 of a submarine showing a person 20 in dotted lines standing on the disk and grasping the handle bars 16 75 with the body 5 collapsed about the lower portion of the person.

Now as the person rises in the water naturally the body will open up acting somewhat like an ordinary parachute in the air 80 but in the reverse direction and the speed of the person will be materially retarded.

If the person desires to rise faster it is only necessary to raise the handle bar 16 thereby sliding the ring 15 upwardly and 85 opening the flat valves 12 the desired distance so that a portion of the water in the body 5 may escape.

It is thought that the construction, operation, utility and advantages of this invention will now be fully understood without a more detailed description thereof.

The present embodiment of the invention has been described in considerable detail merely for the purposes of exemplification since in actual practice it will attain the features of advantage enumerated as desirable in the statement of the invention and the above description. It is apparent that changes in the details of construction, the sizes and

in the materials and in the combination and arrangement of parts may be resorted to without departing from the spirit or scope of the invention as hereinafter claimed or sacrificing any of its advantages.

5 Having thus described my invention, what I claim as new is:

1. An apparatus of the class described comprising a stand, a post rising from the stand, a body disposed about the stand, openings in the body, valves associated with the opening, and means operable from the post for opening the valves.

15 2. An apparatus of the class described comprising a stand, a post rising from the stand, a body disposed about the stand, openings in the body, valves associated with the opening, and means operable from the post for opening the valves, said body being collapsible.

20 3. An apparatus of the class described comprising a stand, a post rising from the stand, a body disposed about the stand, openings in the body, valves associated with the opening, and means operable from the post for opening the valves, said body being collapsible, and of a concavo-convex construction with the concaved side upwardly when extended.

30 4. An apparatus of the class described comprising a stand, a post rising from the stand, a body disposed about the stand, openings in the body, valves associated with the opening, and means operable from the post for opening the valves, said body being collapsible, and of a concavo-convex construction with the concaved side upwardly when extended, a plurality of cables attached to the outer edge of the body and engaged with the upper portion of the post.

40 5. An apparatus of the class described comprising a stand, a post rising from the stand, a body disposed about the stand, openings in the body, valves associated with the opening, and means operable from the post for opening the valves, said body being collapsible, and of a concavo-convex construction with the concaved side upwardly when extended, a plurality of cables attached to the outer edge of the body and engaged with the upper portion of the post, said means for operating the valve comprising cables attached to the valve, a ring slideable on the post and said last mentioned cable being attached to the ring.

55 6. An apparatus of the class described comprising a stand, a post rising from the stand, a body disposed about the stand, openings in the body, valves associated with the opening, and means operable from the post for opening the valves, said body being collapsible, and of a concavo-convex construction with the concaved side upwardly when extended, a plurality of cables attached to the outer edge of the body and engaged with the upper portion of the post, said means for operating the valve comprising cables at-

tached to the valve, a ring slideable on the post and said last mentioned cable being attached to the ring, a pair of loops on the upper side of the stand so that a person may place his feet therein.

70 In testimony whereof I affix my signature.

RAYMOND A. TAYLOR.
